WET VACUUM-PUMP OF THE ROTARY TYPE.

1,157,703.

Specification of Letters Patent. Patented Oct. 26, 1915.

Application filed October 31, 1913. Serial No. 798,535.

To all whom it may concern:

Be it known that I, MAURICE LEBLANC, a citizen of the Republic of France, residing at Val-sur-Seine, Croissy, Seine-et-Oise, France, have made a new and useful Invention 5 in Wet Vacuum-Pumps of the Rotary Type, of which the following is a specification.

The condenser of the applicant company 10 described in U. S. A. Patents No. 984278 dated 14 February 1911 and No. 984435 dated 14 February 1911, has been practically applied as a rotary dry vacuum pump for the purpose of withdrawing the air and 15 non-condensable gases of a condenser, either of the surface or the jet type, and forcing them into a space where a higher pressure prevails. Certain processes have been described in U. S. A. Patent No. 511817 dated 20 7th August 1909 of the said company for transforming the said pump into a wet vacuum pump, that is to say, a pump capable of withdrawing from a surface condenser not only the air and the non-condensable 25 gases but also the water of condensation.

The present invention has for its object a new arrangement whereby this transformation of the rotary dry vacuum pump mentioned just above into a wet vacuum pump 30 may be carried out in practice. This result is obtained in the manner which will now be described with reference to the single figure of the accompanying drawing.

The rotary pump is constituted as described in the patents mentioned above, by 35 a turbine wheel furnished with a crown of blades E and driven in the direction of the arrow by any suitable kind of motor. The fixed nozzle D directs water upon the crown 40 of blades which sprays them in cone-shaped showers into the chamber G which is in communication with the pipe H and the diffuser K. At another part of the periphery of the movable wheel a suction conduit A is provided arranged in any suitable or 45 convenient manner and issuing at a suitable distance from the orifice of the nozzle. The water to be withdrawn from the condenser is supplied to this conduit.

The moving blades communicate kinetic 50 energy to the water of condensation and propel it in the direction of the spray of water issuing from the air pump in such a manner that the water from the condenser, the water from the air pump, and the air 55 withdrawn by the pipe B are simultaneously forced into the diffuser K.

Experience shows that the speed of the water spray from the air pump is not appreciably diminished by this action and that 60 consequently the pneumatic power of the air pump is not altered.

I claim—

1. A vacuum pump comprising a casing having a liquid inlet port, an air inlet port, 65 a liquid and air discharge port, a rotatable wheel located within said casing, a nozzle for delivering liquid to an annular row of blades mounted on the wheel and a passage communicating with the liquid inlet port 70 for delivering liquid to the opposite sides of the blades from the nozzle.

2. A pump comprising a rotatable wheel, an annular row of blades mounted on the impeller, a nozzle located on one side of said 75 blades for delivering ejecting liquid thereto, means for delivering additional liquid to the other side of said blades, and a casing inclosing said wheel and having a port through which the liquid delivered to said 80 wheel is discharged.

3. A vacuum pump comprising a rotatable wheel, an annular row of laterally projecting blades mounted on said wheel, a liquid discharge nozzle located within the ring of 85 blades for delivering liquid to the blades, a casing surrounding the wheel and provided with an air inlet port, a passage for delivering liquid to the outer edges of the blades, and an air and liquid discharge port, 90 through which the liquid delivered to the blades is discharged.

4. A vacuum pump comprising a rotatable wheel, an annular row of laterally projecting blades mounted on said wheel, a liquid 95 discharge nozzle located within the ring of blades for delivering liquid to the blades, a casing surrounding the wheel and pro-

vided with an air inlet port, a passage located ahead of the nozzles, with relation to the direction of motion of the blades, for delivering liquid to the outer edges of the 5 blades, and an air and liquid discharge port, through which the liquid delivered to the blades is discharged.

In witness whereof I have hereunto set my hand in presence of two witnesses.

MAURICE LEBLANC.
